UNITED STATES PATENT OFFICE

MARSHALL MUNCE, OF RICHMOND, VIRGINIA

REFRIGERATION APPARATUS

Application filed November 18, 1930. Serial No. 496,475.

The present invention relates to refrigerating apparatus of the compression-expansion type and particularly to apparatus of this class adapted for use in connection with 5 ice-making plants, although not limited to such use.

Commercial ice plants as heretofore designed and constructed have frequently required the use of two complete refrigerating 10 units, each including a compressor, a condenser, and a work circuit, one unit being occupied exclusively with the cooling of the brine required for ice manufacture and the second unit being required to maintain an 15 ice storage room or chamber at the desired temperature for the continued storage of blocks of ice. Generally speaking also, these units have been of different capacities, i. e., the unit employed to cool the brine having 20 a larger capacity than the unit employed in maintaining the ice storage chamber at the desired low temperature. Ice plants having refrigerating apparatus of this general type have been installed at many points and are 25 in successful operation. The present invention has for one object the improvement of the conventional two-unit refrigerating apparatus by the provision of means enabling the work circuits or cooling coils of both 30 units to be supplied with refrigerant from the compressor of one unit, the improved mechanism being so designed that the compressor and condenser of either unit may be connected to both work circuits at the will 35 of the operator, the compressor and condenser of the second unit being adapted to be cut out.

It will be understood that in a two-unit refrigerating apparatus, as heretofore designed and constructed, the two units are independently operable and that, should either the compressor or condenser, or cooling water supply system of one condenser fail, this unit must be kept out of operation until repairs 40 are effected. In accordance with the present invention, the two refrigerating units are so interconnected that, upon failure of either the compressor or condenser of one unit, the work circuit or cooling coil of such unit may 45 be connected to the compressor or condenser

of the second unit. As a result of this novel arrangement, it is therefore possible for the operator to cut out of action the motor and compressor of either unit for repairs, or for other reasons, without at the same time interfering with the operation of the plant considered as a whole, both work circuits being supplied with the necessary amount of refrigerant, which refrigerant is taken from the condenser of that unit which, for the time being, remains active. Naturally also the compressor and condenser of one unit may be cut out and shut down for any other reason, as, for instance, when the full capacity of the plant is not demanded. The invention is 55 particularly applicable to refrigeration apparatus of the "flooded system" type.

A further object of the invention is the provision of an improved automatically operating compressor starting mechanism whereby the working period of the compressors, or either of them, is reduced to a minimum length of time for the accomplishment of the work in hand, the compressor being automatically started and stopped in accordance with the demand upon the work circuit. Again, it is an important object of the invention to provide an improved refrigerating apparatus of the compressor-condenser type which includes means for insuring that the 70 compressor is in operation only when an adequate supply of cooling water is being supplied to the condenser mechanism.

Thus, means is provided for detecting the presence or absence of water pressure in the 75 main which connects the water pump to the cooling tower of the apparatus. The water pump is caused to start and stop automatically in accordance with the demand upon the associated cooling coil or work circuit. Pressure built up by the pump in the main which leads from its outlet is sufficient to cause the movement of a diaphragm or piston type of pressure responsive device, and the movable element of this device is connected to an electric switch which controls the flow of current to the compressor motor. When the water pump is started, therefore, this pressure responsive device is promptly actuated and the compressor motor switch closed. Upon stop- 80

page of the pump or decrease in pressure of the water in the outlet main thereof for any other reason, the pressure responsive device immediately effects the opening of the compressor motor circuit so that the operation of the motor is stopped. The apparatus as an entirety is therefore safeguarded in one of the most important respects, i. e., it is impossible to operate the compressor motor unless an adequate supply of water is being pumped to the condenser. It is not possible, therefore, for the apparatus to build up excessive pressures in the mains due to unexpected failure of the water supply or the water supply means.

In the following paragraphs the invention will be described in detail, and in the accompanying drawings one form thereof is illustrated. It will be understood, however, that the invention is susceptible of very considerable modifications in using or applying the same in the industrial arts, the design and arrangement of its specific elements being susceptible of a very considerable modification in adapting the apparatus to various tasks.

In the drawings:

Figure 1 is a schematic view of a two-unit refrigerating apparatus of the compression-expansion type, the apparatus shown having been designed for use in connection with an ice-making plant;

Figures 2 and 3 are additional schematic views of portions of the apparatus shown in Figure 1, Figure 2 illustrating only those parts shown in Figure 1 which are in effective operation when one of the compressors is in operation, and Figure 3 illustrating only the effective parts which are in operation when the other compressor is active; and

Figure 4 is a further schematic view of the automatic starting mechanism for one of the compressors.

The apparatus disclosed diagrammatically in Figure 1 comprises two refrigerating units, the first being intended for the manufacture of ice in blocks and the second being intended only for use in maintaining the blocks manufactured by the first unit at a low temperature so that the ice blocks will not melt. The ice-making unit is generally of larger capacity than the unit intended primarily for cooling purposes only, but it will be understood that the relative sizes of the two units have no bearing upon the invention, as these units may be of the same or different capacities, depending upon the circumstances of the particular installation.

In the drawings the compressor of the first unit or freezing unit is indicated at 10, the condenser at 11, and the work circuit or cooling coil at 12. These elements are only diagrammatically illustrated, as they may be, and preferably are, of conventional type. It may be added, however, that the cooling

coil or work circuit of this unit comprises vertically spaced parallel conduits 13 and 14 connected by a series of short conduits or tubes 15. The end of the lower conduit 14, which is disposed in a generally horizontal plane, is provided with a drain outlet controlled by a valve 16, and the opposite end of this conduit opens into a suction tank or surge drum indicated at 17. Similarly, one end of the upper pipe 13 opens into this surge drum. Suitable pipes or conduits are provided for connecting the compressor to the condenser, the condenser to the cooling coil or work circuit, and the work circuit to the compressor so that a complete circulatory system for the refrigerant, which is preferably ammonia, is provided.

The compressed gas from the compressor passes into the compressor outlet main 18 and thence into a main 19 which conducts the compressed and heated refrigerant to the condenser 11. From the condenser 11 the refrigerant, which is, by the action of the condenser, reduced to liquid form, passes into a main 20, through a float valve 21 positioned along the main at a suitable point, and thence into the surge drum 17, the surface of the body of liquid refrigerant in this drum normally standing at or about the level indicated by the dotted line 21. In circulating through the work circuit or cooling coil, the refrigerant passes from drum 17 into the lowermost horizontal main 14, thence upward through pipes 15 to the return main 13, and thence back to the tank 17. From the top of the surge drum or suction trap 17, refrigerant gas is constantly removed through a refrigerant return main 22, the opposite end of which is connected to the intake of the compressor 10.

So long as the compressor 10 is in operation, the refrigerant is compressed, condensed, expanded, and recompressed in the customary and well-known manner, the space around the work circuit or cooling coil unit 12 being reduced thereby in temperature to the proper degree. Any space may be cooled by the operation of the unit, but in a preferred application of the apparatus the system of pipes comprising the work circuit is immersed in a brine tank diagrammatically indicated at 23, cans of water being lowered into the brine tank for the manufacture of ice in well-known manner.

The second refrigeration unit is substantially the same in its general construction as that just described. This second unit includes the compressor 30, condenser 31, float valve 32, suction trap or surge drum 33, and a work circuit or cooling coil 34. The main for conducting refrigerant from the compressor to the condenser is indicated at 35, the main leading from the condenser to the surge drum at 36, and the main for conduct-

ing the refrigerant gas from the surge drum back to the compressor at 37.

Liquid refrigerant passes from the surge drum 33 into the lower reach of the cooling coil 34 and flows, in the direction of the arrow, in the cooling coil, reentering the surge drum 33 at about a point midway between the top and bottom thereof, as shown in the drawings.

10 With the exception of certain valves, etc., hereinafter to be more specifically referred to, I have now described the essential features of both refrigerating units and will hereinafter set forth the means whereby it 15 is rendered possible for the operator to cut out of action the compressor and condenser of one unit and to operate both cooling coils or work circuits from the remaining compressor and condenser. This means, in the 20 present embodiment of the invention, comprises essentially three valve controlled mains indicated at 40, 41, and 42, respectively, the main 40 connecting conduit 20 to conduit 36, the main 41 leading from the 25 surge drum 33, at or about a point midway of the height of this drum, to the upper main 13 of the cooling unit 12, and the conduit 42 connecting the refrigerant gas return mains 22 and 37. Mains 40, 41, and 42 are provided with valves indicated at 43, 44, and 30 45, respectively, by means of which the flow of refrigerant may be controlled or wholly interrupted.

So long as it is desired to operate the two 35 units independently, all three of these valves are closed. If it is desired to supply both cooling coils or work circuits from the compressor 10, all three of the valves should be opened and, at the same time, valve 46 in 40 main 20, valve 47 in main 36, and valve 48 in main 37 closed, thus cutting out the compressor 30 and condenser 31. With the valves just mentioned in the positions set forth, it will be obvious that the compressed refrigerant will flow as before, through main 19 45 to the condenser 11. From condenser 11 the condensed and cooled refrigerant passes through main 20, into main 40, and thence to the surge drum 33. The refrigerant passing 50 into surge drum 33 circulates through the cooling unit 34 as before, excess of refrigerant required by cooling unit 34 entering drum 33 being returned to the cooling unit 12 through main 41. The gas which evaporates 55 from the liquid refrigerant in drums 33 and 17 and the associated cooling coils passes through mains 22 and 37, respectively, and thence through main 22 into the compressor. In this manner compressor 10 and condenser 60 11 serve to supply both cooling coils.

Assuming that it be desired to cut out compressor 10 and condenser 11 and to provide refrigerant for both cooling units by the operation of compressor 30 and condenser 31, it 65 will be seen that it is only necessary to

manipulate certain of the valves diagrammatically shown. Thus, valve 50 is closed, together with valve 43, the motor of compressor 10 being stopped prior to the closure of these valves. Compressor 10 and condenser 11 are therefore cut out of action. Valves 47 and 48 are opened. Action of the compressor therefore forces the refrigerant under pressure through the condenser 31 and thence through main 36 to the surge tank 33. The liquid refrigerant in the surge tank is circulated in part through cooling coil 34 and in part through the cooled unit 12, the main 41 conducting a portion of this refrigerant to the upper main 13 of the cooling unit 12, as before. Mains 22 and 37 are connected directly to the intake of compressor 30, valve 45 being open. Obviously there is a gravity flow of refrigerant to main 41 as the coil 34, which is primarily intended for 70 cooling an ice storage room diagrammatically indicated at 55 and is generally placed adjacent the ceiling of the storage room, is at a higher elevation than the cooling unit 12 for the brine tank or other ice-making instrumentality.

From the above description it will be clear that the apparatus disclosed enables the operator to operate the refrigerating units independently whenever this is desired or to 75 throw the entire load of both cooling units upon one compressor, should the necessity or desirability of doing so ever arise. The novel apparatus, therefore, possesses important advantages over those of analogous nature heretofore designed or suggested, as the plant may be operated to very nearly its full capacity with one compressor entirely out of 80 action. My improved system therefore insures great flexibility and likewise provides 85 a greater increased margin of safety against plant shut-down due to one compressor or condenser being damaged or rendered inoperative. It will, of course, be obvious to one skilled in the art that the arrangement 90 of mains, compressors, condensers, etc., forming the component elements of the apparatus may be greatly changed without departure from the spirit of the invention in adapting 95 the same to various plants and different 100 classes of work.

A second feature of the invention is rather diagrammatically illustrated in Figure 4 of the drawings and comprises essentially a compressor starting means which includes a positive safeguard against operation of the compressor at a time when cooling water is, for 105 any cause, not being pumped to the condenser, thus avoiding the possibility of the development of high pressure in the refrigerant mains with consequent leakage or explosion. In Figure 4 of the drawings, the compressor is indicated at 60, the compressor motor at 61, the water pump at 62, water pump motor at 63, and condenser at 64. A 110 115 120 125 130

water collecting receptacle or sump is indicated at 65 and water main at 66, by means of which water is withdrawn from this sump by the pump 62. The water pump outlet main, or discharge main, is indicated at 66a, this main leading, in the present instance, to a cooling tower of conventional type diagrammatically indicated at T, from which tower it finds its way through the condenser 64 and again into the sump 65. A main for conducting the compressed refrigerant gas from the compressor 60 to the condenser 64 is indicated at 78, and a main for conducting the cooled and condensed refrigerant from the condenser 64 to the work circuit is indicated at 67.

A conventional motor starter of the magnetic type is interposed in the electric supply mains for the compressor starter 60, this motor starter being diagrammatically indicated at 68, and a similar magnet type motor starter in the electrical main leading to the water pump motor 63 is diagrammatically indicated at 69. The control switch of motor starter 69 is adapted to be closed upon the energization of a circuit 70 which includes a solenoid type electromagnet, diagrammatically indicated at 71, and a thermostatically operated switch 72 adapted to be positioned in a space to be cooled, as, for instance, in a brine tank, indicated diagrammatically at 73, and within which tank the cooling coil or work circuit 74 of the motor-compressor cooling unit is also positioned.

The thermostatically actuated switch 72 may be any one of a number of well-known types and need not be described in detail. It is sufficient to say that this switch automatically closes when the temperature of the brine in the brine tank 73 rises to a predetermined degree. As a result of the closing of the circuit 70, the motor starter 69 is actuated and the electrical connection between the source of power P and the motor 63 completed. The water pump 62 immediately commences operation to circulate the water from the sump 65 to the cooling tower and condenser. A branch main 75 extends from the water pump outlet main 67 to a pressure operated switch, diagrammatically indicated at 76. The details of this switch need not be herein set forth inasmuch as it also may be of conventional type, such as a diaphragm or piston operated switch or the like.

Immediately after water pump 62 begins to pump water to the cooling tower T, a considerable pressure is built up in the main 66a, which pressure is communicated through the branch main 75 to the pressure actuated switch 76. Switch 76 is immediately operated by this water pressure to close the circuit indicated at 77, this circuit being energized from the source of power P and including a solenoid magnet 79 which, in reality, comprises a portion of the magnetic motor starter

switch mechanism 68. As a result, the compressor motor 61 is energized, the compressor starts, and the process of compression, condensation, evaporation, and cooling in the refrigeration circuit is commenced.

From the above description it is clear that the compressor will at all times remain inoperative except when the water pump 62 is in operation and water is actually passing to the cooling tower and hence to the condenser. Should the supply of water from the sump (or any other suitable source) fail so that the pressure in the main 66a falls below a predetermined minimum, the pressure actuated switch 76 automatically opens the circuit 77, and following this the compressor motor starting mechanism 68 operates to open the motor circuit switch so that the compressor motor immediately becomes de-energized and stops. It is thus clear that it is impossible for the compressor to operate except when a suitable supply of cooling water is being delivered by the water pump and that, should either the supply of water to the pump fail or breakage in the water supply system develop, or should the water pump 62 stop, the compressor motor 61 would likewise stop. Hence the system is positively safeguarded against damage due to operation of the compressor at a time when the condenser is inadequately supplied with water.

It will be further noted that the operation of the system as a whole is entirely automatic, the action of both the water pump and the compressor motor being initiated by the closing of the circuit 70 by operation of the thermostatically controlled switch 72 in the brine tank. The usual manual operation of the water pump motor switch is therefore dispensed with entirely. The improved system is more economical in its operation inasmuch as the water motor and compressor are not called into operation until the temperature in the brine tank or other cooling space has risen to the exact degree which has been determined in advance as the limit of permissible temperature rise, and the operation of both the water pump and compressor is discontinued immediately upon falling of the temperature of the brine tank, or other cooled space, below the permissible maximum temperature predetermined. It is found that this system of full automatic control is more economical both from the standpoint of wear and tear on the machinery, operator's time, and current consumption than the method of hand operation heretofore practiced.

Having thus described the invention, what is claimed as new and desired to be secured by Letters Patent is:—

1. Refrigerating apparatus including, in combination, two adjacent and independently operable refrigerating units each comprising a compressor, a condenser, a work circuit

and conduits for conducting a refrigerant from the compressor to the condenser, from the condenser to the work circuit, and from the work circuit back to the compressor, and
 5 means for cutting out the compressor and condenser of either unit and connecting the work circuit thereof to the conduits of the second unit so that a single compressor and condenser supplies refrigerant to both work
 10 circuits.

2. Refrigerating apparatus including, in combination, two adjacent and independently operable refrigerating units each comprising a compressor, a condenser, a work circuit and conduits for conducting a refrigerant from the compressor to the condenser, from the condenser to the work circuit, and from the work circuit back to the compressor, and means for circulating a controlled
 15 amount of refrigerant from one work circuit through the other work circuit.

3. Refrigerating apparatus for use in a commercial ice plant comprising a cooling coil adapted to be immersed in a brine tank, and a second cooling coil adapted to be placed in an ice storage space, two independently operable compressors, a condenser associated with each compressor, and a system of piping and valves whereby the refrigerant from
 25 either compressing and condensing unit may be caused to circulate through both cooling coils at the will of the operator.

4. Refrigerating apparatus for use in a commercial ice plant comprising a cooling coil adapted to be immersed in a brine tank, a second cooling coil adapted to be placed in an ice storage space, said second cooling coil being positioned at a higher elevation than the first mentioned coil, a compressor, a condenser, means for conducting refrigerant from the condenser to the second cooling coil, means for conducting a portion of the refrigerant supplied to the second cooling coil, by gravity, to the first cooling coil, and means
 45 for conducting refrigerant from both cooling coils to the compressor.

5. Refrigerating apparatus comprising two refrigerant circulating systems, each including a compressor and a cooling coil, the cooling coil of one system being positioned above the cooling coil of the second system, and means for conducting refrigerant by gravity from the upper cooling coil to the lower.

6. Refrigerating apparatus comprising two refrigerant circulating systems, each including a compressor and a cooling coil, said systems being independently operable, means for disconnecting either compressor from its associated cooling coil, and a second means for connecting such last mentioned cooling coil to the other compressor, for the purpose set forth.

7. Refrigerating apparatus comprising two refrigerant circulating systems, each including a compressor and a cooling coil, said

systems being independently operable, means for disconnecting one compressor from its associated cooling coil, and means for connecting the thus disconnected cooling coil to the other circulatory system, said last mentioned means including a conduit for conducting gaseous refrigerant from said last mentioned cooling coil to the active compressor and a conduit for conducting liquid refrigerant from this cooling coil to the other cooling coil.

8. The combination set forth in claim 7 in which the two cooling coils are at different elevations and liquid refrigerant is caused to flow from one to the other by gravity.

9. Refrigerating apparatus comprising two cooling coils, two compressors, means for conducting gaseous refrigerant from both cooling coils to either compressor, and means for conducting liquid refrigerant from such compressor to both cooling coils.

10. Refrigerating apparatus comprising two cooling coils, two compressors, means for conducting gaseous refrigerant from both coils to either compressor, and means for conducting liquid refrigerant in series through said cooling coils.

11. Refrigerating apparatus comprising two compressors, two cooling coils disposed one above the other, means for cutting out one compressor, means for conducting gaseous refrigerant from both cooling coils to the then active compressor, means for conducting liquid refrigerant from the compressor to the upper cooling coil, and means for conducting liquid refrigerant from the upper cooling coil to the lower cooling coil.

12. The combination set forth in claim 11 in which the upper cooling coil includes a surge drum, and said last mentioned means comprises a conduit for conducting overflow liquid refrigerant from the surge drum by gravity to the lower cooling coil.

In testimony whereof I hereunto affix my signature.
